TREATMENT OF FABRICS

Maurice M. Kasanof, Bronx, N. Y.; David R. Kasanof and Abraham Kriegel executors of said Maurice M. Kasanof, deceased

Application November 7, 1932, Serial No. 641,522

7 Claims. (Cl. 26—55)

My present invention relates generally to the treatment of fabrics for purposes such as drying, shrinking, cleaning and the like and in particular to the treatment of fabrics in tubular form by the action thereon of fluids.

Among the general objects of my invention are the provision of an arrangement whereby the treatment of the fabric may be varied in accordance with the requirements of the particular fabric to be treated, and the provision of an arrangement whereby the treatment may be controlled so as to vary the effects to be produced on any given fabric.

In a copending application Ser. No. 641,521 filed Nov. 7, 1932, I have shown apparatus for the fluid treatment of tubular fabrics in which the fabric is supported between spaced end members so as to form a tubular chamber, the outer walls of which are constituted by the fabric. The treating fluid is discharged into this chamber and emerges from the chamber by passing through the walls of the fabric. By causing the fabric to move over the end members, the entire length of the fabric is treated, but at any one time only a portion of it is exposed to such treatment. The object to be attained by the apparatus disclosed in said copending application was stated to be the provision of a treating chamber of such length that a substantial portion of the fabric would be exposed at one time, and the provision of relatively adjustable end members whereby the length of the treating chamber, and consequently the area of fabric exposed at one time, may be varied to suit different fabrics and to obtain different effects on a given fabric. These end members are also constructed so as to offer little resistance to the passage of the fabric thereover.

In my Patent #1,711,094 of April 20, 1929, I have disclosed an arrangement whereby tubular fabrics may be subjected to the action of air for drying purposes, and subsequently to the action of steam, all of which is accomplished in one operation as the fabric is passed through the apparatus.

In the embodiment of my invention disclosed in the present application, I attain the combination of the air treatment with the steam treatment as shown in my aforementioned patent, with the substantially proportioned and adjustable treating chamber of my aforementioned application by using the steam treatment member of the patent in place of one of the end members of the application.

Another object of my invention is the provision

of a discharge arrangement for the treating fluid whereby the resistance to its discharge will be minimized.

I attain the above and other objects by the use of steam and air for treating purposes as disclosed in a general way in the aforementioned patent, but instead of the air treating arrangement of the patent I provide a treating chamber of which one end is constituted by the steam dome and the other end by a guide member for the fabric, movable in relation to the steam dome, so as to provide a treating chamber adjustable in extent and permitting a substantial area of the fabric to be exposed to treatment at one time. The air discharge into this chamber takes place freely through the open end of the air conduit, in contradistinction to the arrangement shown in the patent wherein air is discharged from a series of restricted openings directly into the fabric.

While I have mentioned the use of steam and air, since these are customarily used in treating fabrics, it is to be understood that other fluids having the desired properties may be used as will readily suggest themselves to those skilled in the art, and it is further to be understood that I use the term fluid in a generic sense to include all media suitable for use in my apparatus for the treatment of fabrics.

The invention, however, is not intended to be restricted to the particular construction and arrangement of parts herein disclosed, nor to the particular application of such construction, nor to the specific methods of operation, as the same may be modified in various particulars or be applied in various relations without departing from the spirit and scope of the invention, a practical embodiment of which has been illustrated and described, without attempting to show all of the various forms and modifications in which the invention might be practiced. It is further understood that while I have described and illustrated embodiments which attain many or all of the enumerated objects, other embodiments may be employed to utilize only a few or even only one of said objects, and not all of them.

For the attainment of the above enumerated objects and such other objects as may herein appear or be pointed out, I have shown an illustrative embodiment of my invention in the drawing, wherein:

Figure 1 is an elevational view of my invention; and

Figure 2 is a similar view on a greatly enlarged

scale with portions broken away to illustrate the details of the apparatus, and the extreme upper portion of the apparatus being illustrated in a different relation to the other parts from that shown in Figure 1.

Upon viewing the drawing it will be observed that the fabric 70 is shown in place in the apparatus in Figure 2, and that by its contact between the surface 16 of steam dome 11 and the periphery of member 38, a chamber is formed of which the fabric itself constitutes the outer wall. Some idea of the extent of this chamber may be formed from an inspection of Figure 1, in which the relative disposition of the parts is more apparent than from Figure 2, in which portions are broken away. It will be observed that due to the spacing between steam dome 11 and member 38, the portion of fabric between those parts is substantial in area, and the extent of such area may be varied either to increase it or to decrease it, by changing the position of member 38 by shifting its position on the conduit 30. This conduit serves to conduct air from supply pipe 36 and fitting 32 into the treating chamber and there it is discharged freely through the open end 31 of the conduit into the chamber and through the fabric.

The fabric may be pulled through the apparatus by any suitable pulling arrangement (not shown), such as drawing rollers, which may be located at the upper end of the apparatus, and, as it moves over the member 38, and the steam dome 11, it is subjected first to an air treatment (between member 38 and surface 16), then to a heat treatment (by the walls 16), next to the direct action of steam, issuing from orifices 14 in the steam dome 11, and into the space 20 formed between 16 and the stretching ring 12 located on the steam dome. It receives another heat treatment serving to dry it and give it a finished appearance, on the surface 22 of the steam dome 11, and from there passes over a spreader or stretcher member 23 and into the pulling device.

In order to insure easy motion and freedom from injury to the fabric 70, the periphery of member 38 is of annular or beaded form and of small area, so as to reduce friction.

To provide adjustability, the annular member 38 is mounted on a split collar 40, engaging conduit 30 and may be made removable therefrom in any suitable and convenient manner such, for instance, as that shown for the part 35 in my Patent #1,648,614 of November 8, 1927. By using this construction, member 38 may be replaced by other similar members of different sizes or of different shapes.

The ring 12 on the steam dome may be similarly made adjustable and removable and it is also made beaded in form to reduce frictional resistance.

The steam dome 11, as illustratively shown, is of the type disclosed in my Patent #1,648,614, above mentioned, and reference is made to that patent for the details of its construction. It is mounted, so as to be readily removable, on the upper ends of steam pipe 13,—receiving its steam from supply pipe 15—and of drain pipe 17, which serves to drain off condensed steam from the steam dome.

Pipes 13 and 17 pass through the air conduit 30 and through cap 34 closing end of fitting 32, and serve to heat the air used for the treatment.

A platform 42 may be provided for the purpose of gathering the fabric before it passes through the apparatus, this being indicated in Figure 2.

When it is desired to use my invention, the

steam dome and annular member are first removed and the fabric slipped over the conduit 30 and gathered over the platform 42. The member 38 is next replaced, as is also the dome 11 and steam is admitted into the dome and air into the conduit 30. The annular guide member is adjusted so as to form a treating chamber of the desired length, that is a length adapted to the character of the fabric to be treated, the character of the treatment, and the speed of passage of the fabric through the apparatus.

The upper end of the fabric is then drawn over member 38, dome 11 and spreader 23 and led into the pulling device, which acts to draw the entire length of fabric through the apparatus.

While the operation of my invention has been described in connection with the treatment of the fabric by two different fluids, it is obvious that for certain purposes the same fluid may be employed in both conduits, or that fluid may be supplied to only one conduit while the other one is not used. For example, steam might be discharged from conduit 30 and also pass into the steam dome, or on the other hand air might be used in conduit 30, while the steam supply is shut off and steam dome 11 is idle, or, again air might be discharged from the steam dome while conduit 30 is idle. Also, steam might be used in conduit 30 and air in steam dome 11. These and other possibilities of use will readily suggest themselves to users of my apparatus.

Having thus described my invention and illustrated its use, what I claim as new and desire to secure by Letters Patent is:

1. Apparatus for treating tubular fabrics having a treating chamber and means for guiding, heating, steam-treating and forming said fabric defining one end of said chamber, means restricted in contact area and adjustable relatively to said first means for guiding said fabric at the other end of said chamber, and the fabric itself constituting the wall of said chamber, means for introducing steam into said steam-treating means, and means for introducing a fluid into said treating chamber.

2. Apparatus of the character described comprising a conduit open at its end to permit the unrestricted discharge of a treating fluid, a second conduit for conducting a second treating fluid located within said first-mentioned conduit, a hollow body having discharge openings for the second fluid carried by the second conduit in spaced relation to the opening of the first conduit, and an annular member adjustably positioned on the first conduit, whereby a tubular fabric may be guided over said annular member and said hollow body and during its passage subjected to the successive action of the two fluids.

3. Apparatus of the character described comprising a conduit open at its end to permit the unrestricted discharge of a treating fluid, a second conduit for conducting a second treating fluid located within said first-mentioned conduit, a hollow body having discharge openings for the second fluid carried by the second conduit in spaced relation to the opening of the first conduit and an annular member having a restricted and rounded peripheral surface adjustably positioned on the first conduit, whereby a tubular fabric may be guided over said annular member and said hollow body with relatively little resistance and during its passage subjected to the successive action of the two fluids.

4. Apparatus of the character described comprising a conduit open at its end to permit the

unrestricted discharge of a treating fluid, a second conduit for conducting a thermally active treating fluid located within said first-mentioned conduit, a hollow body having discharge openings for 5 the second fluid carried by the second conduit, in spaced relation to the opening of the first conduit, and adapted to heat, to guide and to form said fabric, and an annular member adjustably positioned on the first conduit, whereby a tubular 10 fabric may be guided over said annular member and said hollow body and during its passage subjected to the successive action of the two fluids and to heat.

5. An apparatus for drying and finishing tubular fabrics comprising a conduit for conducting hot air, a pair of members over which the tubular fabric is drawn, forming an elongated annular drying chamber defined by the conduit, the tubular fabric and the said pair of members, one of 15 the said members being provided with instrumentalities for stretching, steam-treating and heating the fabric, and an opening in the said conduit for introducing hot air into the said elongated annular chamber.

20 25 6. An apparatus for drying and finishing tubular fabric comprising an outer conduit for conducting hot air, a pair of members over which

the tubular fabric is drawn, forming an elongated annular drying chamber defined by the conduit, the tubular fabric and the said pair of members, the outer conduit being provided with an opening wherethrough hot air is introduced 5 into the said elongated drying chamber, one of the said pair of members being provided with instrumentalities for stretching, steam-treating and heating the fabric, and an inner conduit for conducting steam to the steam-treating and heating 10 member.

7. An apparatus for drying and finishing tubular fabric comprising a conduit for conducting hot air, a pair of members over which the tubular fabric is drawn, forming a suspended annular 15 drying chamber defined by the conduit, the tubular fabric and the said pair of members, an opening in the said conduit for introducing hot air into the said suspended chamber, a platform at the base of the conduit upon which the wet fabric 20 is piled, the lower one of the said pair of members being adjustable in relation to the said platform so that the pile of wet fabric may be immediately suspended, formed into an annular chamber, and dried. 25
